UNITED STATES PATENT OFFICE.

HARRY HEATON, JR., OF KING'S NORTON, ASSIGNOR TO CHARLES KINGSTON WELCH, OF COVENTRY, ENGLAND.

DESIGN FOR A TIRE-COVER FOR BICYCLES.

SPECIFICATION forming part of Design No. 24,455, dated July 2, 1895.

Application filed February 21, 1895. Serial No. 639,283. Term of patent 14 years. Patented in England June 27, 1894, No. 235,173.

To all whom it may concern:

Be it known that I, HARRY HEATON, Jr., a citizen of Great Britain, residing at King's Norton, in the county of Worcester, England, have invented a certain new and original Design for a Cover for Pneumatic Tires, (for which I have obtained a certificate of registration in Great Britain, No. 235,173, bearing date June 27, 1894,) of which the following is a specification.

My new design consists of a ribbed cover for pneumatic tires. The ribs pass circumferentially round the tread of the cover; but instead of the ribs being continuous, as is commonly the case with ribbed covers, each rib is corrugated or waved and the elevations and depressions in the parallel ribs are so disposed as to be out of phase with each other.

In the accompanying drawings, Figures 1, 2, and 3 show a portion of the cover with the new design of ribs. Fig. 1 is a plan with the

cover spread flat. Fig. 2 is a transverse section, and Fig. 3 is an edge elevation of the cover shown flat. Fig. 4 is a side view of a complete article manufactured in accordance with my design.

The ribs are marked A and the corrugations are plainly shown at Fig. 3, where B B are elevations in the rib in front, while C C are elevations in the next rib, corresponding in positions to the depressions which alternate with the elevations B B.

I claim—

The design for tire covers, as herein shown and described.

In witness whereof I have hereunto set my hand in presence of two witnesses.

HARRY HEATON, JNR.
